UNITED STATES PATENT OFFICE.

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC SPEED-CONTROL EQUIPMENT.

Application filed January 25, 1922. Serial No. 581,676.

To all whom it may concern:

Be it known that I, THOMAS H. THOMAS, a citizen of the United States, residing at Edgewood, in the county of Allegheny and State of Pennsylvania, have invented new and useful Improvements in Automatic Speed-Control Equipments, of which the following is a specification.

This invention relates to automatic train speed control equipments, and more particularly to an equipment of the character disclosed in the prior Patent No. 1,316,205 of Walter V. Turner, dated September 16, 1919, and my pending application, Serial No. 292,209, filed April 23, 1919.

With train control equipments of the above character, three permissible train speed limits are provided; a high speed limit which is permitted in a clear block, a medium speed limit, which is permissible in a caution block, and a low speed limit, in a danger block.

Under certain conditions, such as at some crossovers, it may be considered desirable and safe to permit the train to proceed at the medium speed limit in order to prevent loss of time as much as possible, although the indication received from the rail may be for low speed.

One object of my invention is to provide means by which a speed controlled train may pass a danger indication, under certain conditions, at the medium speed limit.

It has heretofore been proposed to provide a train speed control equipment in which the engineer must acknowledge a caution indication or he will be penalized by the apparatus operating to reduce the speed of the train to the low speed limit, and a further object of my invention is to provide means for compelling the engineer to acknowledge a low speed indication under penalty of having the train brought to a stop.

In some cases, locomotives equipped with speed control apparatus are employed both for passenger and for freight service and another object of my invention is to provide means for setting the apparatus to operate at the high passenger range of speed limits when operating as a passenger locomotive and at the lower freight range of speed limits when the locomotive is employed in freight service.

Another object of my invention is to provide means for cutting the speed control apparatus out of action in case of an emergency but which is adapted to prevent the apparatus from being cut in again except by an authorized person. 55

Another object of my invention is to provide means by which the speed control apparatus may be cut in or out of action in normal service but only as determined by an authorized person. 60

Another object of my invention is to provide means by which only an authorized person may set the apparatus for freight or passenger service under certain conditions and restrictions. 65

It is considered desirable to provide a train speed control equipment which compels the engineer to operate the train in accordance with the signal indications independently of the automatic control by the train speed control apparatus, so that in 75 case of possible failure of either the engineer or the train control apparatus, the other control agency will be effective to control the train.

In this connection, another object of my invention is to provide improved means for compelling the engineer to perform his duties. 80

Another object of my invention is to provide a train speed control equipment in 85 which the release of the brakes is controlled by manipulation of the engineer's brake valve device instead of a separate manually operated release valve, so that the engineer has only to operate the brake valve in the 90 manner that he should under the particular circumstances in order to properly control the train.

Other objects and advantages will appear in the following more detailed description 95 of the invention.

In the accompanying drawings; Fig. 1 is a diagrammatic sectional view of an automatic train speed control equipment embodying my improvements, showing the relative 100 positions of the various parts when the indication from the track is for clear or high speed and the train at a stand still, with the speed governor stationary, the apparatus being set for passenger service; Fig. 2 a diagram, illustrating the operation of charging 105

the train control apparatus; Fig. 3 a diagram, showing the operation when a train in a clear block exceeds the high speed limit; Fig. 4 a diagram showing the operation when a train at high speed receives a caution or medium speed indication and the indication is acknowledged; Fig. 5 a diagram showing the operation when a train at high speed receives a caution indication and the indication is not acknowledged; Fig. 6 a diagram showing the operation when a train running at medium speed receives a low speed indication and the indication is acknowledged; Fig. 7 a diagram showing the operation when a train at medium speed receives a low speed indication and the indication is not acknowledged; Fig. 8 a partly sectioned detail view of the freight and passenger service setting means; Fig. 9 a face view thereof; and Fig. 10 a sectional view of the emergency cut out locking means.

As shown in the drawings, with particular reference to Fig. 1, the train speed control equipment may comprise an automatic brake valve device 1, an independent brake valve device 2, a main reservoir 3, an acknowledging valve device 4, and a train speed control valve mechanism. The train speed control valve mechanism may comprise a pipe bracket 5, to which is attached a speed controlled governor valve mechanism 6; a section including a brake application valve device 7, a change speed valve device 8, an equalizing discharge valve device including a piston 9 and valve 10, a stop reservoir piston 11 and valve 12, and a stop piston 13 and valve 14; a section including a selector valve device 15, a medium speed valve device 16, an acknowledging piston 17 and valves 18 and 19, a high to medium speed blow down valve piston 20 and valve 21, and a medium to low speed blow down valve piston 22 and valve 23. Associated with the pipe bracket 5 is a high speed magnet 24 and double beat valve 25, a medium speed magnet 26 and double beat valve 27, a feed valve device 28, a feed valve reservoir 29, a reduction reservoir 30, an equalizing reservoir 31, a stop reservoir 32, a high to medium blow down reservoir 33, and a medium to low blow down reservoir 34.

The change speed valve device 8 may comprise a differential piston having differential piston heads 35 and 36, acted upon in opposite directions by springs 37 and 38 tending to maintain the pistons in the intermediate neutral position, and operating a slide valve 39. The application valve device 7 comprises a piston 40 and slide valve 41, the selector valve device 15, a piston 42 and slide valve 43, and the medium speed valve device, a piston 44 and slide valve 45.

The speed governor portion may

prise governor balls 46, operatively connected to a governor shaft 47 which is rotated according to the speed of the train by means of bevel gears 48 which are operatively connected to a driving axle of the locomotive. As the governor balls 46 fly out according to the speed of the train, a sliding spindle 49 is shifted and thereby a crosshead 50 which is secured to the spindle. The crosshead 50 is adapted to operate a series of valves having valve stems of varying lengths as follows: Passenger high to medium speed blow down timing valve 51, freight high to medium speed blow down timing valve 52, passenger high speed application valve 53, freight high speed application valve 54, passenger low speed application valve 55, freight low speed application valve 56, freight medium speed application valve 57, passenger medium speed application valve 58, freight medium to low speed blow down timing valve 59, and passenger medium to low speed blow down timing valve 60.

In connection with the train speed control apparatus above enumerated, means are provided by which a clear or high speed rail indication causes the high speed magnet 24 to be energized and the medium speed magnet 26 to be deenergized, a caution or medium speed indication causes the medium speed magnet 26 to be energized and the high speed magnet 24 to be deenergized, and a danger or low speed indication causes both magnets 24 and 26 to be deenergized.

Charging the system.

Assuming that the rail indication is for high speed, the high speed magnet 24 will be energized and the medium speed magnet 26 deenergized. Fluid under pressure from the main reservoir 3 will flow through pipe 61, passage 62, and passage 63 to valve chamber 64 of the selector valve device 15 and thence through the feed groove around piston 42 to piston chamber 65, thus permitting the spring to move piston 42 to its inner position. Fluid also flows from passage 62 through passage 66 to valve chamber 67 of the medium speed valve device 16, and the piston 44 will be shifted to its outer position, since piston chamber 68 is connected to the atmosphere through passage 69 and exhaust port 70 controlled by the double beat magnet valve 27 of magnet 26. Fluid flows to piston chamber 71 of the change speed valve device 8 from passage 62, through passage 72, past the double beat valve 25, passage 73, passage 74, past open valve 18 to passage 128, cavity 75 in selector slide valve 43, and passage 76, and fluid is supplied to piston chamber 77 of piston 36 from valve chamber 64 of the selector valve device 15, through passage 78. The valve chamber 79 of the change speed

- valve device 8 is charged through passage 62, and passage 80, the passage 80 also supplying fluid to the valve chamber 81 of the application valve device 7. From valve 5 chamber 81, fluid equalizes through a restricted port in the piston 40 to piston chamber 82, permitting spring 83 to shift piston 40 to its inner release position. Fluid from the main reservoir 3 is also supplied to the 10 rotary valve chamber 84 of the automatic brake valve 1 from valve chamber 81 of the application valve device 7, when the slide valve 41 is in release position, through passage 85 and pipe 86.
- 15 Fluid is supplied from the main reservoir 3 through passage 87 to the feed valve device 28 and thence, at the pressure as reduced by the feed valve device, to the feed valve reservoir 29. The high to medium speed reservoir 33 is charged with fluid at feed valve pressure when the parts are in the high speed position, through passage 88, 20 passage 89, cavity 90 in selector slide valve 43 and passage 91, the passage 91 also leading to the upper face of the high to medium speed blow down valve piston 20. The opposite side of the piston 20 is supplied with fluid at feed valve pressure from passage 89, through passage 92.
- 25 In the position of the medium speed valve device 16, as shown in Fig. 1, the medium to low speed blow down reservoir 34 is not charged, but when said valve device is shifted to the inner medium speed position, 30 the reservoir 34 is charged from passage 89, through passage 93, cavity 94 in medium speed slide valve 45, passage 95, and past the medium to low speed valve piston 22 to passage 96. In the inner or medium speed position of slide valve 45, the stop reservoir 32 is also charged with fluid at main reservoir pressure from the medium speed valve chamber 67, through cavity 97 in slide valve 45 and passage 98.
- 35 With the rotary valve 99 of the acknowledging valve device 4 in normal position, as shown in Fig. 1, the acknowledging reservoir 100 is charged with fluid at main reservoir pressure from pipe 86, through 40 cavity 101 and pipe 102.
- 45 The brake pipe 103 is charged from the brake valve device 1, as usual with the standard locomotive brake equipment and the brake pipe is connected by a passage 55 104 with the chamber at the under side of the equalizing piston 9 and the equalizing reservoir, which is connected to the opposite side of the equalizing piston 9, is charged from the brake pipe 103 through 60 passage 104 past check valve 105, passage 106, cavity 107 in application slide valve 41, and passage 108.
- 65 The principal charging features hereinbefore described are shown somewhat more clearly in the diagram, Fig. 2, wherein only the ports and passages actually involved in the charging operation are shown.
- Train receiving a clear or high speed indication from the track and speed exceeds the high speed limit.*
- In this case, when the high speed limit is exceeded, the governor cross head 50 will be moved by the action of the governor balls 46 so as to unseat the high speed passenger application valve 53 and fluid under pressure will be vented from piston chamber 82 of the application valve device 7 through passage 109. The application piston 40 and slide valve 41 then move out to application 75 position, in which the equalizing reservoir 31 and hence the upper face of the equalizing piston 9 are connected to the reduction reservoir 30 by way of passage 110, cavity 111 in slide valve 41, and passage 112. The reduction reservoir is then at atmospheric pressure, since in the release position of the slide valve 41, the reduction reservoir passage 112 was connected by cavity 111 to 80 exhaust port 113, and consequently the venting of fluid under pressure from the upper face of the equalizing piston 9 and from the equalizing reservoir, causes movement of the piston to unseat the equalizing discharge valve 10 and thereby vent fluid from 85 the brake pipe 103 to the atmosphere through passage 114, cavity 115 in slide valve 41, and exhaust port 113. The reduction in brake pipe pressure thus produced then causes an application of the 90 brakes in the usual manner to thereby effect a reduction in the speed of the train.
- 95 By venting the equalizing reservoir into the reduction reservoir 30, the reduction in brake pipe pressure as effected by the operation of the speed control apparatus is limited to a predetermined degree. The operation above described is shown more clearly in the diagram, Fig. 3 of the drawings. The movement of the application slide 100 valve 41 to application position also cuts off communication to passage 85 and pipe 86, through which fluid is supplied from the main reservoir to the automatic brake valve 1. This prevents the supply of fluid to the 105 brake pipe through the brake valve device while the slide valve 41 is in application position.
- 110 In the application position of slide valve 41, the passage 109, leading to the piston chamber 82 of the application valve device 7, is connected by cavity 116 with a pipe 117, leading to the seat of the rotary valve 118 of the brake valve device 1 and in running, release, and holding positions of the 115 brake valve, said pipe is connected by a cavity 119 with an exhaust port 120. It will thus be seen that after the brakes have been applied, the application piston 40 will remain in application position, due to the 120

fact that the piston chamber 82 is connected to the atmosphere through the automatic brake valve 1, and that the brakes cannot be released unless the engineer moves the 5 brake valve handle 121 to lap position or to a brake application position in which the pipe 117 is cut off from the exhaust. When the engineer moves the brake valve handle to lap position, the pipe 117 is lapped and 10 thus permitting the equalization of fluid pressure through the restricted port in piston 40 on opposite sides of said piston, the spring 83 will return the piston 40 and slide valve 41 to release piston, so that 15 the brake pipe 103 may then be recharged and the brakes released by the subsequent movement of the brake valve handle to release position. It will be understood that the brakes cannot be released by operation 20 of the brake valve as above described until the speed of the train has been reduced below the high speed limit, so as to permit the high speed application valve 53 to close.

25 *Train running at high speed receives a caution or medium speed indication from the track. (Indication acknowledged.)*

When a train running at high speed enters a caution or medium speed block, the 30 engineer should acknowledge the indication before the speed control mechanism functions and the present apparatus is so constructed that if the caution indication is not acknowledged, the speed control mechanism 35 will be immediately set for low speed, but if the indication is acknowledged, it will be set for the medium speed limit in a predetermined time, dependent upon the speed of the train.

40 In this case, to acknowledge the medium speed indication, the engineer should operate the handle 175 of the acknowledging valve device 4 to shift the valve 99 to the acknowledging position, in which fluid under 45 pressure is supplied from the acknowledging reservoir 100 to the acknowledging piston 17 by way of a port through the valve 99, passage 122, pipe 123, passage 124, cavity 125 in the application slide valve 41, and passage 126. The piston 17 is then shifted, causing the piston valve 18 to close communication from passage 74 to passage 128, leading to the piston chamber 71 of the 50 change speed valve device 8 and opening the valve 19, so that the piston chamber 65 of the selector valve device 15 is connected to the atmosphere through passage 127, past the valve 19 and past the valve 18 to passage 74, and thence through passage 73 55 to the exhaust port 129 of the high speed magnet 24, the magnet 24 being deenergized and the medium speed magnet 26 energized upon receiving a medium speed indication. The piston 42 then shifts the slide valve 43 60 to its outer position in which the spring

side of the high to medium speed blow down valve piston 20 is vented to the atmosphere through passage 91, cavity 90 in selector slide valve 43, passage 130, cavity 131 in rotary valve 132, passage 133 and past the governor blow down timing valve 51. The spring side of the valve piston 20 is also connected to the high to medium speed reservoir 33 which is now charged with fluid under pressure as previously described. 70 When the pressure in the reservoir 33 and on the spring side of the valve piston 20 has been reduced to a predetermined degree, dependent upon the size of the exhaust opening created by the timing valve 51, which in turn depends upon the speed of the train, the valve piston 20 will be shifted outwardly by the feed valve pressure acting under its seat, so as to open the valve 21 and thereby 75 vent fluid from piston chamber 77 of change speed valve device 8, through passage 78, past the valve 21 to exhaust port 134. The change speed valve device 8 is then moved to its right hand or medium speed position, 80 due to its differential piston construction. 85

In the medium speed position of the valve device 8, the piston chamber 82 of the application valve device is connected to the governor passenger medium speed application valve 58, through passage 109, passage 135, cavity 136 in slide valve 39, and passage 137 and if the speed of the train exceeds the medium or caution speed limit, the valve 58 will be opened and fluid will be vented from piston chamber 82 of the application valve 95 device 7, so that said valve device will be operated to effect an application of the brakes in the manner hereinbefore described. After the speed has been reduced to the medium speed limit, the brakes may be released 100 by manipulation of the brake valve device 105 as hereinbefore described.

It may be noted here that when the selector piston 42 has been shifted to its outer position, a cavity 141 in selector slide valve 110 43 connects passage 127 directly with passage 128, leading to the high speed double beat valve 25, so that the piston chamber 65 will be maintained at atmospheric pressure and the selector valve device 15 will be held 115 in its outer position, so long as the high speed magnet 24 remains deenergized.

When a caution indication is received, the medium speed magnet 26 is energized and fluid from the main reservoir will be supplied to the piston chamber 68 of the medium speed valve device 16 by way of passage 72, past the double beat magnet valve 27, and through passage 69. The piston 44 will then shift the slide valve 45 to its inner 120 position, in which the stop reservoir 32 is charged with fluid under pressure from the main reservoir through passage 62, cavity 97 in slide valve 45, and passage 98.

In this position of the slide valve 45, the 130

medium to low speed reservoir 34 is also charged with fluid at feed valve pressure through passage 93, cavity 94 in slide valve 45, passage 95, through the spring chamber 5 of the blow down valve piston 22 and passage 96. The charging of the stop reservoir 32 and the medium to low speed reservoir 34 in the medium speed position of the slide valve 45 is for use when the train enters a low 10 speed block as will be hereinafter described.

The diagram of Fig. 4 illustrates somewhat more clearly than Fig. 1, the operation when the train enters a medium speed block and the indication is acknowledged.

15 *Train running at high speed receives a caution or medium speed indication from the track. (Indication not acknowledged.)*

In this case, since the acknowledging piston 17 is not operated, the valve 19 will not be opened, and consequently, the deenergization of the magnet 24 upon receiving a caution indication will be effective to vent fluid from the piston chamber 71 of the change 20 speed valve device 8, instead of from the piston chamber 65 of the selector valve device 15 by way of passage 76, cavity 75 in selector slide valve 43, passage 128, past the open piston valve 18 and through passages 25 74 and 73 to exhaust port 129. Since the piston chamber 71 is vented to the atmosphere, the change speed valve device will be shifted to the left hand or low speed position, due to its differential construction.

30 35 In this position of the change speed valve device 8, the piston chamber 82 of the application valve device 7 is connected to the passenger low speed application valve 55 through passage 135, cavity 136 in slide valve 39, passage 138, cavity 139 in rotary valve 132, and passage 140. If the speed of the train exceeds the low speed limit, the valve 55 will be opened by the operation of the governor balls 46 and fluid will be vented 40 from the piston chamber 82 of the application valve device 7, so that the application valve device will be shifted to application position to effect an application of the brakes, as hereinbefore described. It will 45 thus be seen that if the engineer does not acknowledge the caution indication, the speed of the train will be reduced to the low speed limit, as a penalty for failure to acknowledge. The above operation is shown 50 55 diagrammatically in Fig. 5 of the drawings.

Train running at medium speed enters a low speed or danger block. (Indication acknowledged.)

60 65 In this case, the low speed indication causes both magnets 24 and 26 to become de-energized. Assuming that the previous caution indication has been duly acknowledged, the selector piston 42 will be in its outer position and will remain there, since the high

speed magnet 24 remains deenergized. The medium speed valve device 16 will be shifted to its outer position, since the deenergization of the medium speed magnet 26 causes the venting of fluid from the piston chamber 68, 70 as hereinbefore described.

If the acknowledging valve device 4 is operated by the engineer upon receiving a danger indication, while the acknowledging piston 17 will be actuated as herein-

75

before described, no further functioning will occur, since the selector piston 42 is already in its outer position, but when fluid is supplied to the piston 17, it is also admitted through passage 142 to the face of stop

80

reservoir piston 11, so that the valve 12 is operated to vent fluid from the stop reservoir 32, the change speed valve device 8 still being in the medium speed position, through passage 98, cavity 97 in medium

85

speed slide valve 45, passage 143, cavity 144 in selector slide valve 43, passage 145, cavity 146 in change speed slide valve 39 the change speed valve device being still in the medium speed position, passage 147, and past the

90

open valve 12 to exhaust port 148. The venting of fluid from the stop reservoir prevents the operation of the stop mechanism and the delayed application is effective by reason of the fact that the shifting of the medium speed slide valve 45 to its outer

95

position connects the spring side of the medium to low blow down valve piston 22 to the passenger medium to low speed blow

100

down valve 60 through passage 95, cavity 94 in slide valve 45, passage 149, cavity 150 in rotary valve 132, and passage 151. The medium to low speed reservoir 34 being connected to the spring side of the valve piston 22 through passage 96, the fluid

105

pressure in said reservoir and in the spring chamber of the valve piston 22 is then vented at the blow down valve 60 at a rate corresponding with the speed of the train, and when the pressure on the spring side

110

of the valve piston 22 has been reduced to a predetermined degree, the valve piston will be operated by feed valve pressure acting below the valve to open the valve 23 and vent fluid from the piston chamber 71 of the change speed valve device 8, through

115

passage 76, cavity 75 in selector slide valve 43, passage 152, cavity 153 in medium speed slide valve 45, passage 154, and past the open valve 23, through passage 155 containing

120

check valve 156, and thence through passage 78, past the open valve 21 to exhaust port 134. Both of the piston chambers 71 and 77 being now at atmospheric pressure, the change speed valve device 8 will be shifted to the left hand or low speed

125

position in which the piston chamber 82 of the application valve device 7 is connected to the passenger low speed application valve 55 through passage 135, cavity 136 in slide

130

valve 39, passage 138, cavity 139 in rotary valve 132 and passage 140, as hereinbefore described. If the train is then running at a speed exceeding the low speed limit the 5 application valve device 7 will then be operated to effect an application of the brakes.

If the low speed or danger indication is not acknowledged by shifting the acknowledging valve 99, then the above described 10 venting of fluid stored in the stop reservoir 32 will not occur and consequently when the change speed valve device shifts to the low speed position, fluid from the stop reservoir 32 will be supplied to the piston 13 15 of the stop valve device through passage 98, cavity 97 in medium speed slide valve 45, passage 143, cavity 144 in selector slide valve 43, passage 145, cavity 146 in change speed slide valve 39, and passage 157. The 20 piston 13 is then operated to open the valve 14 and vent fluid directly from the application piston chamber 82, through passage 158 to the atmosphere. The brakes will then be applied by operation of the application 25 valve device 7 and the train will be brought to a complete stop, as a penalty for failure of the engineer to acknowledge the danger indication (see Fig. 7).

At crossovers, there may be a section of 30 track which is not equipped for signal indication, and not being energized by the signal circuits, the result is that both of the magnets of the train control apparatus on the locomotive will then be in the de- 35 energized state and the apparatus is of course operated as though a danger indication had been received. It may be desired to proceed over such a crossover at medium speed in order to avoid unnecessary delay, 40 and accordingly I have provided means whereby under the above conditions the train may proceed past the crossover at medium speed.

For this purpose, a short section of track 45 in advance of or immediately preceding the crossover is energized so as to give a clear or high speed indication to the train and assuming that the train is already proceeding at or below the medium speed limit, with 50 the train control apparatus set for the medium speed, then when the train enters the clear section, the train control apparatus on the locomotive will be set for high speed. The reason for doing this is so that the 55 high to medium speed reservoir 33 may be recharged with fluid under pressure in the manner hereinbefore described in connection with charging the system in a high speed block.

60 The train control apparatus will now be in the high speed position shown in Fig. 1, with the change speed valve device 8 in high speed position, the selector valve device 15 in its inner position, and the medium speed valve device 16 in its outer position.

While passing over the above mentioned clear or high speed section of track, the engineer operates the acknowledging device 4, so that fluid under pressure is supplied from the acknowledging reservoir 100 70 through passage 126 to piston 17. Said piston is then shifted, so that piston valve 18 cuts off communication from passage 74 to passage 128 and at the same time the valve 19 is opened by the movement of 75 piston 17, so that piston chamber 65 of the selector valve device 15 is connected to the double beat valve 25 of high speed magnet 24 through passage 127 past the open valve 19 to passage 74, and thence through 80 passage 73 to the double beat valve 25.

When the train passes from the clear section to the deenergized crossover, the high speed magnet 24 will be deenergized, the 85 medium speed magnet 26 remaining in its previous state of deenergization, as will be evident.

The deenergization of magnet 24 operates to shift the double beat valve 25 so that communication between passages 72 and 73 is 90 closed and communication is opened from passage 73 to exhaust port 129.

Fluid under pressure will therefore be vented from piston chamber 65 of the selector valve device 15 through passage 127, 95 past open valve 19 to passage 73 and exhaust port 129.

The piston 42 is then shifted to its outer position, in which piston chamber 71 of the change speed valve device is connected 100 to the valve 23 of the medium to low blow down through passage 76, cavity 75 in slide valve 43 of the selector valve device 15, passage 152, cavity 153 in slide valve 45, and 105 passage 154. It will therefore be evident that under the above conditions, fluid will not be vented from piston chamber 71, so as to permit the shifting of the change speed valve device 8 to low speed position until 110 the valve 23 is opened.

At the same time, piston chamber 77 of the change speed valve device 8 is connected to valve 21 of the high to medium blow down through passage 78, so that fluid 115 will be vented from piston chamber 77 dependent upon the opening of valve 21.

In the outer position of slide valve 43 of the selector valve device 15, the spring side of the valve piston 20 of the high to medium blow down and the charge at high to medium reservoir 33 are connected to the medium speed blow down timing valve 51 through passage 91, cavity 90 in slide valve 43, passage 130, cavity 131 in rotary valve 132, and 120 passage 133. When the pressure in the reservoir 33 and on the spring side of the valve piston 20 has been reduced to a predetermined degree, dependent upon the size of the exhaust opening created at the timing valve 51, which in turn depends 125 130

upon the speed of the train, the valve piston 20 will be shifted, so as to open valve 21 and thereby vent fluid from the piston chamber 77 of the change speed valve device 8 to exhaust port 134. If the train were still on the crossover, the valve device 8 would then be shifted to its right hand or medium speed position in which the connections are made for limiting the speed 10 of the train to the medium speed limit, as hereinbefore described, but the time period required to blow down the reservoir 33 is such that the train will have passed over the crossover before the valve 21 is opened.

15 During the period that the above operation is taking place, fluid is also being vented from the spring side of the medium to low blow down valve piston 22 and the reservoir 34, through passage 95, cavity 94 in slide valve 45, passage 149, cavity 150 in rotary valve 132, passage 151, and the medium to low speed blow down timing valve 60. After the pressure on the spring side of the valve piston 22 has been reduced 25 to a predetermined degree by venting at the valve 60, said valve piston will be operated to open the valve 23. It will now be noted that although the opening of valve 23 will connect passage 154, which is at this time 30 open to the low speed piston chamber 71 of the change speed valve device 8, to vent passage 155, fluid cannot be vented from said piston chamber until the valve 21 opens, since passage 155 is connected to passage 35 78 leading to the valve 21.

The blow down timing valves 51 and 60 are adapted to vary the exhaust opening through which fluid is vented from the blow down valve pistons 20 and 22 as the speed 40 of the train varies, so that the higher the speed, the larger the exhaust opening created and since the medium to low timing valve 60 operates at a lower speed than the high to medium timing valve 51 a larger 45 exhaust opening is created at the valve 60 than at the valve 51 for a given train speed.

It will therefore be evident that were it not for the fact that the exhaust from the valve 23 is controlled by the opening of 50 valve 21, the earlier opening of valve 23, due to the more rapid venting of fluid from the spring side of valve piston 22 would operate to vent fluid from the low pressure piston chamber 77 of the change speed valve device, before the valve piston 20 is operated to open valve 23.

By connecting the exhaust from valve 23 to valve 21, the opening of valve 23 remains ineffective until the valve 21 opens.

60 The result of the above functioning is that at crossovers and the like, the preceding short clear section of track sets the apparatus to high speed position and then when the train passes from the clear section 65 to the deenergized crossover, the time period

provided by the operation of the valve piston 20 and valve 21 before the change speed valve device 8 can be operated to either its medium or its low speed position is sufficient to permit the train to pass over the 70 crossover without having to reduce its speed. The train having passed over the crossover, the medium speed indication being received, the train can then proceed at the medium speed limit. 75

In some cases, it may be desired to operate a locomotive in both freight and passenger service, and with the automatic train control apparatus installed, it is then necessary to provide means whereby the speed 80 control apparatus will control the train at one range of train speed limits when the locomotive is operating in freight service and at a higher range of speed limits, when the locomotive is being employed in passenger service. For this purpose, I provide two sets of speed controlled application valves and two sets of blow down timing valves, and a manually operated rotary valve 132 having one position for connecting the passenger valves to the speed control apparatus, another position for connecting the freight valves to the speed control apparatus, and a third position, in which both sets of valves are cut out. 85 90 95

In Fig. 1 of the drawings, the passenger valves are shown as connected up, the stems of the valves being of such length as to give the desired range of speed limits for passenger service, and in the freight operating position of the valve 132, the freight valves are connected up, the stems of these valves being of greater length than the stems of the corresponding passenger valves, so that the range of speed limits will be lower to 100 105 correspond with those described for freight service.

As shown in Figs. 8 and 9 of the drawings, the valve stem 159 for operating the rotary valve 132, by which the speed control apparatus is set for either passenger or freight service, may be provided with a locking arrangement comprising a lock barrel 160, mounted in the casing 161 and having a key hole 162 for receiving a key. 110 The turning of the key operates a latch member 163, which is adapted to engage slots 164 and 165, according to the position of the operating handle 166 and the stem 159. When the latch member 163 engages 115 in one slot, the member 159 and valve 132 are locked against movement from one operating position and when said member engages in the other slot, the valve 132 is locked against movement from the other operating position. 120 125

The key may, according to one scheme of control, be in the custody of an authorized person who will employ the key to set the speed control apparatus for passenger or 130

for freight service, or according to another scheme of operation, the engineer may carry the key and thus control the setting of the apparatus. In the latter case, a sealed soft wire loop 167 may be threaded across the key hole 162, so that it is necessary to break the wire in order to insert the key and then the fact that the engineer has readjusted the apparatus will be made known to an inspector who will make a record of the fact, so that if the engineer has made an unwarranted adjustment of the apparatus, it will be made known to the proper authorities.

15 It may sometimes be necessary, in an emergency, for the engineer to have the power of cutting the speed control apparatus out of action, and for this purpose, a cut out cock 168 may be provided for controlling communication through which the fluid pressure in piston chamber 82 of the application valve device 7 is vented.

In order to prevent the engineer from cutting the speed control apparatus in or out at will regardless of whether an emergency condition exists, means are provided by which if the engineer once turns the cock 168, the same cannot be turned again without the sanction of another person. For this purpose two lock plugs 169 and 170 are provided, the lock plug 169 having an operative connection with the cut-out cock 168 and being operable by a key 171 which is carried by the engineer. The other plug 170 is operable only by a key 172 which is in the custody of a designated person. A pin 173, associated with the plug 170 is adapted to interlock with the plug 169 in such manner that when the key 171 is turned by the engineer to operate the cock 168, so as to cut off communication to the application piston chamber 82 and thus prevent the speed control apparatus from working, the key and the cock cannot be again turned so as to open said communication, without first inserting the key 172 in the other plug and turning the plug so as to rotate the pin 173 out of the path of the plug 169.

With the above arrangement, it will be seen that while the engineer may, in case of an emergency, cut the speed control apparatus out of action, he is unable to again cut the apparatus into service. He must then report the fact to a designated authority, who will have the key 172 in his possession and who can reset the apparatus as required, by inserting the key 172 as hereinbefore described.

The acknowledging mechanism is so designed that the engineer cannot avoid acknowledging by allowing the handle of the acknowledging valve to remain in the acknowledging position, since the supply of fluid for operating the acknowledging piston 17 is limited to the charge contained in

the acknowledging reservoir 100 and therefore, with the acknowledging valve in acknowledging position, the fluid pressure in the reservoir 100 would quickly leak off through the restricted port in the piston 17 to the exhaust port open to the opposite side of the piston, thus permitting the piston 17 to return to its non-acknowledging position.

Having now described my invention, what I claim as new and desire to secure by Letters Patent, is:—

1. In a train speed control apparatus, the combination with means on the train for imposing a medium speed limit and means for imposing a low speed limit, of means controlled by the medium speed means for suppressing the action of the low speed means.

2. In a train speed control apparatus, the combination with means on the train for imposing a medium speed limit and means for imposing a low speed limit, of means for suppressing the action of the low speed means until the medium speed means acts.

3. In a train speed control apparatus, the combination with a change speed valve device having a medium speed position and a low speed position, of a valve mechanism for varying the fluid pressure on said valve device to shift same to the medium speed position and a valve mechanism for varying the fluid pressure on said valve device to shift same to the low speed position, the medium speed valve mechanism controlling communication through which the low speed valve mechanism varies the fluid pressure on said valve device.

4. In a train speed control apparatus, the combination with a change speed valve device having a medium speed position and a low speed position, of a valve mechanism for venting fluid pressure from said valve device, means for delaying the operation of said valve mechanism, and a second valve mechanism for also venting fluid pressure from said valve device, the communication through which the second valve mechanism vents fluid pressure being controlled by the first valve mechanism.

5. In a train speed control apparatus, the combination with mechanism for determining the speed limit of the train, of slow acting means for effecting the operation of said mechanism to impose one speed limit on the train, slow acting means for effecting the operation of said mechanism to impose a lower speed limit on the train, and means for suppressing the operation of the second slow acting means until the first slow acting means operates.

6. In a train speed control apparatus, the combination with a change speed valve device movable to a low speed position upon a reduction in fluid pressure, of means controlled according to the signal indication for vent-

- ing fluid from said valve device, a slow acting valve mechanism for also venting fluid from said valve device, a selector valve device movable by a reduction in pressure to 5 a position for connecting said change speed valve device to said slow acting valve mechanism, and valve means under the control of the engineer and having one position for connecting said change speed valve device 10 to said signal indication controlled means and another position for connecting said selector valve device to said signal indication controlled means.
7. In a train speed control apparatus, 15 the combination with means on the train for imposing a low speed limit upon receiving a low speed indication, of means operative upon a change from a medium to a high speed indication for delaying the 20 action of the low speed means when a low speed indication is received.
8. In a train speed control apparatus, the combination with means on the train for imposing a low speed limit upon receiving 25 a low speed indication, of means operative in advance of receiving a low speed indication for delaying the action of the low speed means when a low speed indication is received.
- 30 9. In a train speed control apparatus, the combination with mechanism on the train capable of imposing a medium speed limit and a low speed limit, of means operative under one condition to cause said mechanism to impose the low speed limit upon receiving a low speed indication and operative under another condition to cause said mechanism to impose a medium speed limit upon receiving a low speed indication.
- 40 10. In a train speed control apparatus, the combination with an application valve device for effecting an application of the brakes and means for operating said valve device when the speed of the train exceeds 45 a predetermined limit, of a reservoir charged with fluid under pressure, a valve device operated by fluid from the reservoir for also effecting the operation of said application valve device, and means under the 50 control of the engineer for venting fluid from said reservoir.
11. In a train speed control apparatus, the combination with a reservoir adapted to be charged with fluid under pressure, of 55 means operable by fluid from said reservoir for effecting a reduction in the speed of the train, means operated upon a change in the signal indication for connecting said reservoir to said means for effecting a reduction 60 in the speed of the train, and means operable by the engineer for venting fluid from said reservoir.
12. In a train speed control apparatus, the combination with a reservoir and means 65 for charging said reservoir with fluid under pressure, of means operated by fluid under pressure for effecting an application of the brakes, means governed by the signal indication for connecting said reservoir to said means for effecting an application of the brakes, and means operable by the engineer for venting fluid from said reservoir. 70
13. In a train speed control apparatus, the combination with an application valve device for effecting an application of the brakes, means for imposing a high, medium, or low speed limit, and means for operating said valve device when the speed of the train exceeds the imposed speed limit, of a reservoir, means for charging said reservoir with fluid under pressure in the medium speed position of the apparatus, a valve device operated by fluid from the reservoir for also effecting the operation of said application valve device, and means under the control of the engineer for venting fluid from said reservoir. 75
14. In a train speed control apparatus, the combination with an application valve device operated upon venting fluid under pressure therefrom for effecting an application of the brakes and means for venting fluid from said valve device when the speed of the train exceeds a predetermined limit, of an engineer's brake valve having a position in which said valve device is connected to an exhaust port. 80
15. In a train speed control apparatus, the combination with an application valve device operated upon venting fluid under pressure therefrom for effecting an application of the brakes and means for venting fluid from said valve device when the speed of the train exceeds a predetermined limit, of an engineer's brake valve having a position in which said valve device is connected to an exhaust port when the application valve device is in application position. 85
16. In a train speed control apparatus, the combination with an application valve device operated by a variation in fluid pressure for effecting an application of the brakes and means for operating said valve device when the speed of the train exceeds a predetermined limit, of an engineer's brake valve for controlling the movement of said valve device to release position. 90
17. In a train speed control apparatus, the combination with an application valve device having a piston operated by a reduction in fluid pressure for effecting an application of the brakes and means for reducing the pressure on said piston when the speed of the train exceeds a predetermined degree, of an engineer's brake valve having a release position in which said piston is connected to an exhaust port and a lap position in which communication from said piston to the brake valve is blanked. 110
18. In a train speed control apparatus, 120
- 125
- 130

- the combination with a speed governor operated according to the speed of the train, of a valve operative to effect a reduction in the speed of the train and operated by said governor when the train speed exceeds a predetermined limit, a valve operative to effect a reduction in the speed of the train and operated by said governor when the train speed exceeds a different predetermined limit, and means for cutting one valve out of operation when the other valve is cut in. 19. In a train speed control apparatus, the combination with a speed governor operated according to the speed of the train, of a valve operative to effect a reduction in the speed of the train and operated by said governor when the train speed exceeds a predetermined limit, a valve operative to effect a reduction in the speed of the train and operated by said governor when the train speed exceeds a different predetermined limit, and manually operable means for connecting either valve into operation. 20. In a train speed control apparatus, the combination with a speed governor operated according to the speed of the train, of two sets of valves, each valve operative to effect a reduction in the speed of the train, one set of valves being operated by the governor through one range of train speed limits and the other set of valves through a different range of train speed limits, and manually operable means for rendering one set of valves effective while the other set remains ineffective. 21. In a train speed control apparatus, the combination with mechanism for imposing one range of train speed limits on the train for one class of service and a different range of train speed limits for another class of service, of a device for adjusting said mechanism to operate at either of said ranges of train speed limits and means for locking said device in either of its adjusting positions. 22. In a train speed control apparatus, the combination with mechanism for imposing one range of train speed limits on the train for one class of service and a different range of train speed limits for another class of service, of a device for adjusting said mechanism to operate at either of said ranges of train speed limits, means for locking said device in either of its adjusted positions, and a key for operating said locking means. 23. In a train speed control apparatus, the combination with mechanism for imposing one range of train speed limits on the train for one class of service and a different range of train speed limits for another class of service, of a device for adjusting said mechanism to operate at either of said ranges of train speed limits, means for locking said device in either of its adjusted positions, a key for operating said locking means, and a tell-tale device for indicating that the key has been used to operate said means. 24. In a train speed control apparatus, the combination with mechanism for imposing one range of train speed limits on the train for one class of service and a different range of train speed limits for another class of service, of a device for adjusting said mechanism to operate at either of said ranges of train speed limits and means for preventing the operation of said device except by an authorized person. 25. In a train speed control apparatus, the combination with mechanism for imposing one range of train speed limits on the train for one class of service and a different range of train speed limits for another class of service, of a device for adjusting said mechanism to operate at either of said ranges of train speed limits and means operable only by a specialized element for controlling the operation of said device. 26. In a train speed control apparatus, the combination with means for cutting said apparatus out of action, of a device for locking said means against operation, a key for operating said device to cut said apparatus out of action, and means for preventing movement of the key and said device from the cut out position. 27. In a train speed control apparatus, the combination with means for cutting said apparatus out of action, of a device for locking said means against operation, a key for operating said device to cut said apparatus out of action, means for preventing movement of the key and said device from the cut out position, and a key for operating said means to permit movement of said device to its cut in position. 28. In a train speed control apparatus, the combination with means by which the speed control apparatus may be cut into or out of action, of a specialized element operative only to effect movement of said means to the cut out position and a separate specialized element operative to permit movement of said means to the cut in position. 29. In a train speed control apparatus, the combination with means by which the speed control apparatus may be cut into or out of action, of mechanism under the control of one person for effecting the operation of said means only to the cut out position and under the control of another person for effecting the operation of said means to the cut in position. 30. In a train speed control apparatus, the combination with a change speed valve device having a medium speed position and a low speed position, of means normally operative to bring the train to a stop upon receiving a low speed indication and acknowledg-

edging means under the control of the engineer for preventing the operation of said means, the operation of said acknowledging means being ineffective in the low speed 5 position of said change speed valve device.

31. In a train speed control apparatus, the combination with a piston and means operated by said piston for modifying the action of the speed control apparatus due 10 to receiving a speed control indication, of a reservoir normally charged with fluid under pressure and a valve under the control of the engineer for supplying fluid from the reservoir to said piston to thereby 15 acknowledge the speed control indication.

32. In a train speed control apparatus, the combination with fluid pressure operated means for acknowledging a signal indication, of a reservoir normally charged with 20 fluid under pressure and a manually operated valve for supplying fluid under pressure for operating said means.

33. In a train speed control apparatus, the combination with means including a fluid pressure operated piston for acknowledging a signal indication, of a reservoir 25 normally charged with fluid under pressure, a manually operated valve having a position for supplying fluid from said reservoir to said piston, and a restricted port for permitting the gradual escape of fluid under pressure supplied to said piston.

34. In a train speed control apparatus, the combination with means for acknowledging a signal indication, of a manually 30 operated device for effecting the operation of said means and means for effecting the movement of the acknowledging means to its normal inoperative position after a predetermined interval of time. 35 40

In testimony whereof I have hereunto set my hand.

THOMAS H. THOMAS.
